[57] CLAIM

The ornamental design for a guard for aerial cable connectors, as shown and described.

DESCRIPTION

FIG. 1 is a perspective view of a guard for aerial cable connectors showing my new design;

FIG. 2 is a side elevational view thereof, the side not shown being identical to the side shown;

FIG. 3 is an end elevational view thereof, the end not shown being identical to the end shown;

FIG. 4 is a top plan view thereof; and,

FIG. 5 is a bottom plan view thereof.
